(57) **CLAIM**

The ornamental design for a garment locker, substantially as shown and described.

DESCRIPTION

FIG. 1 is a perspective view of a first embodiment of a garment locker according to my new design, with the two locker doors shown closed and with portions of the locker shown in dashed lines not forming a part of my design;

FIG. 2 is a right frontal elevation view thereof, showing the two locker doors in opened position, and with portions of the locker shown in dashed lines not forming a part of my design;

FIG. 3 is a front elevation view thereof, with the locker doors closed; and

FIG. 4 is a front elevation view thereof, with the locker doors shown open.

FIG. 5 is a perspective view of a second embodiment of a garment locker according to my new design, with the two locker doors shown closed and with portions of the locker shown in dashed lines not forming a part of my design;

FIG. 6 is a right frontal elevation view thereof, showing the two locker doors in opened position, and with portions of the locker shown in dashed lines not forming a part of my design;

FIG. 7 is a front elevation view thereof, with the locker doors closed; and

FIG. 8 is a front elevation view thereof, with the locker doors shown open;

FIG. 9 is a perspective view of a third embodiment of a garment locker according to my new design, with the two locker doors shown closed and with portions of the locker shown in dashed lines not forming a part of my design;

FIG. 10 is a right frontal elevation view thereof, showing the two locker doors in opened position, and with portions of the locker shown in dashed lines not forming a part of my design; FIG. 11 is a front elevation view thereof, with the locker doors closed; and

FIG. 12 is a front elevation view thereof, with the locker doors shown open;

FIG. 13 is a perspective view of a fourth embodiment of a garment locker according to my new design, with the two locker doors shown closed and with portions of the locker shown in dashed lines not forming a part of my design;

FIG. 14 is a right frontal elevation view thereof, showing the two locker doors in opened position, and with portions of the locker shown in dashed lines not forming a part of my design; FIG. 15 is a front elevation view thereof, with the locker doors closed; and,

FIG. 16 is a front elevation view thereof, with the locker doors shown open.

The exterior sides, rear, top and bottom of the garment locker, shown in broken lines, do not form a part of my design.
